[57] ABSTRACT

Accurate analog addition and subtraction are performed in a proportional fluidic amplifier of the stream interaction type in which a pair of control nozzles are superposed, one atop the other, so as to issue their respective control streams against the same point in the power stream flow path.

PURE FLUID ADDITION AND SUBTRACTION

BACKGROUND OF THE INVENTION

The present invention relates to fluidic amplifiers and more particularly to fluidic amplifiers of the stream interaction type which may be employed to add two analog pressure signals.

Accurate addition of analog pressure signals has not been possible with prior art stream interaction type fluidic amplifiers because of the control nozzle locations in these amplifiers. More specifically, if two pressure signals are to be added they must produce a net power stream deflection which is proportional to the sum of the signal pressures. This requires that both signals be applied against the same power stream location; this is true because if one control signal issues upstream of the other, the former has a greater effect than the latter in deflecting the power stream. In prior art amplifiers, control streams representing input signals are issued co-planar with one another and the power stream and thus of necessity must act against different downstream locations of the power stream.

The above problem exists even in those prior art fluidic amplifiers in which control passages are joined to issue multiple control signals from one nozzle. In this regard, the multiple signals, though issuing from a common nozzle, still issue from different downstream locations of that nozzle and hence have different effects on power stream deflection. Moreover, there is significant interaction between the control signals in this configuration and this causes inaccuracies in signal addition as monitored by power stream deflection.

It is an object of the present invention to provide a fluidic amplifier of the stream interaction type capable of accurately adding two input pressure signals.

It is another object of the present invention to provide a fluidic element of the stream interaction type in which power stream deflection serves as an accurate indication of the sum of two input pressure signals.

It is still another object of the present invention to provide a fluidic amplifier of the stream interaction type capable of performing both analog addition and analog subtraction operation on two input pressure signals.

SUMMARY OF THE INVENTION

The invention comprises superposing two control nozzles, one atop the other, so that control streams issued therefrom operate against respective halves of the power stream at the same location in the power stream flow path. In one embodiment, the amplifier is fabricated from two cover plates, each having half of the amplifier configuration formed in one face. The two plates are joined, face-to-face, with a barrier plate disposed between the cover plates in the region of the control nozzles. Each control nozzle is then divided into two superposed control nozzles arranged to effect power stream displacement from the same point in the power stream flow path.

BRIEF DESCRIPTION OF THE DRAWINGS

The above and still further objects, features and advantages of the present invention will become apparent upon consideration of the following detailed description of one specific embodiment thereof, especially when taken in conjunction with the accompanying drawings, wherein:

FIG. 1 is a plan view of a fluidic amplifier constructed according to the principles of the present invention;

FIG. 2 is a side view of the embodiment of FIG. 1; and

FIG. 3 is a schematic diagram illustrating the operation of the fluidic amplifier of FIG. 1.

DETAILED DESCRIPTION OF THE PREFERRED EMBODIMENT

Referring specifically to FIGS. 1 and 2 of the accompanying drawing, there is illustrated a proportional fluidic amplifier 10 of the stream interaction type. The cavities, passages and nozzles required to provide amplifier 10 are formed in respective

surfaces of each of flat plates 11 and 13. Plates 11 and 13 are sealed together, face-to-face, in fluidtight relationship by machine screws, clamps, adhesives or other suitable manner. For the sake of facilitating the understanding of the present invention, plates 11 and 13 are illustrated as being composed of clear plastic; however, it should be understood that any material compatible with the working fluid may be used in the construction of amplifier 10.

The amplifier comprises a power nozzle 15 adapted to receive pressurized fluid and respond thereto by issuing a power stream of the fluid into an interaction region 17. Left and right sidewalls 19, 21 of region 17 are set back sufficiently to prevent the power stream from locking on to either sidewall due to boundary layer phenomena. Vent holes 23 and 25 are bored completely through either one or both of plates 11 and 13 to provide fluid communication between ambient pressure and the interaction region 17.

Left and right outlet passages 27 and 29 respectively are disposed at the downstream end of interaction region 17 in receiving relation with the power stream. Outlet passages 27 and 29 are positioned symmetrically with respect to the longitudinal axis of power nozzle 15; however, this is a matter of design choice and not limiting on the scope of the invention.

Amplifier 10 is provided with a pair of right control nozzles A and B superposed on one another with nozzle A atop nozzle B as viewed in FIG. 1. Formation of nozzles A and B is accomplished in much the same manner as the other passages and nozzles in amplifier 10; that is, nozzle A, is formed in plate 11 and nozzle B in plate 13. Simple joinder of plates 11 and 13 would thus provide a single right control nozzle; however, a thin barrier plate 31 is inserted between plates 11 and 13 in the region of the right control nozzle so that two distinct superposed nozzles A and B are formed. Barrier plate 31 may fit into respective depressions in plates 11 and 13, which depressions would be configured to the contour of barrier plate 31 and which would be cut to a much shallower depth in plates 11 and 13 than are control nozzles A and B. Alternatively, and as illustrated, barrier plate 31 may be sufficiently thin as to not require such depressions in plates 11 and 13. In either case, the barrier plate permits independent pressure signals to be applied to control nozzles A and B and to remain isolated until issued as control streams into interaction region 17.

In like manner left control nozzles C and D are provided, separated by a barrier plate 33, wherein nozzle C is superposed above nozzle D as viewed in FIG. 1.

The effect of the superposed control nozzles is to permit two independent pressure signals to operate at the same point in the power stream flow path. This is illustrated schematically in FIG. 3 wherein signals applied to right control nozzles A and B are shown to act at the same point and signals applied to left control nozzles C and D are shown to act at the same point. In the symmetrical configuration illustrated, nozzle pair A and B act on the power stream in a manner exactly opposite to that in which nozzle pair C and D act.

In actuality, the control stream issued from control nozzle A may be considered as acting on the top half of the power stream in the vicinity of the control nozzle outlet opening. Likewise, the control stream issued from control nozzle B may be considered as acting on the bottom half of the power stream in this vicinity. The overall effect is to permit issuance of two control streams having like effectiveness as regards power stream deflection.

65 Addition, as comprehended by the present invention, is monitored in terms of power stream deflection. Power stream deflection, in turn, is measured as a function of the differential pressure, ΔP_o , appearing across outlet passages 27 and 29. Thus, if we assume that two pressure signals to be added are applied to control nozzles A and B, the differential pressure appearing across passages 27 and 29 is proportional to the sum of the input signal pressures. Likewise, the differential pressure of opposite sense, that is, appearing across passages 29 and 27, is proportional to the sum of the input signal pressures at control nozzles C and D.

The two plate (11 and 12) configuration of amplifier 10 is possibly the most simply constructed embodiment of the present invention, but clearly not the only possible construction. The barrier plates may, for example, be constructed integrally with the plate or plates in which the amplifier passages are formed. For example, in the three-layer fluidic amplifier construction exemplified by U.S. Pat. No. 3,122,165, the barrier plates may be part of the center layer. Additionally, where a single cover plate is employed to seal the passages formed in a further plate (as described in U.S. Pat. No. 3,275,013) the barrier plates may either be inserts adapted to fit in the control passages of the latter plate or alternatively may be formed as part of the latter plate.

The present invention has also been found to provide excellent results in performing analog subtraction operations on input pressure signals. In particular, it was found that excellent analog subtraction was achieved by applying the two input signals to control ports A and D respectively or to control ports B and C respectively. As described above in relation to the addition operation, subtraction is monitored in terms of power stream deflection produced by the difference between the input signal pressures. The differential pressure ΔP_o appearing across outlet passages 27 and 29 serves as a measure of power stream deflection.

While I have described and illustrated one specific embodiment of my invention, it will be clear that variations of the details of construction which are specifically illustrated and described may be resorted to without departing from the true spirit and scope of the invention as defined in the appended claims.

I claim:

1. A fluidic amplifier of the stream interaction type comprising:
  - an interaction region;
  - a power nozzle responsive to application of pressurized fluid thereto for issuing a power stream of fluid into said interaction region;
  - means constraining said power stream to flow in a predetermined plane;
  - at least one outlet passage disposed for receiving portions of said power stream as a function of power stream deflection; and
  - at least first and second control nozzles superposed one atop the other and disposed to respond to application of respective fluid signals thereto for issuing respective control streams into said interaction region and into deflecting relationship with said power stream at the same point in the power stream flow path.
2. The fluidic amplifier according to claim 1 wherein said amplifier is of the proportional type and is constructed from two plates, each plate having a flat surface into which the con-

figuration of said amplifier is cut, the plates being joined face-to-face in fluidtight relationship with the respective amplifier configurations in precise registration, and wherein said superposed first and second control nozzles are formed by a barrier plate interposed between said two plates in the region of said control nozzles.

5 3. The fluidic amplifier according to claim 1 further comprising a second outlet passage disposed to receive a portion of fluid from said power stream as a function of power stream deflection, said first and second outlet passages being disposed to provide a differential output pressure as a function of power stream deflection.

10 4. The fluidic amplifier according to claim 3 further comprising third and fourth control nozzles superposed one atop the other and disposed to respond to application of respective fluid signals thereto for issuing respective control stream into deflecting relationship with said power stream at the same point in the power stream flow path, said third and fourth control nozzles being further disposed to issue their respective 15 control stream in substantial opposition to the control stream issued by said first and second control nozzles.

20 5. The fluidic amplifier according to claim 4 wherein said amplifier is of the proportional type.

6. The fluidic amplifier according to claim 5 wherein said 25 amplifier is constructed from two plates, each plate having the various passages, interaction region and nozzle configurations of the amplifier cut into a respective face thereof, the two plates being joined face-to-face in fluidtight relationship with the amplifier configuration of both plates in precise registration and wherein first and second barrier plates are disposed 30 between the plates in the region of said control nozzles so that each of said first, second, third and fourth control nozzles is defined between a cut-out portion of a respective plate and a respective one of the barrier plates.

35 7. An analog fluidic amplifier of the stream interaction type comprising:

an interaction region;
power nozzle means responsive to application of pressurized fluid thereto for issuing a power stream of fluid into said interaction region;

means constraining said power stream for flow in a single plane through said interaction region;

a pair of outlet passages in said single plane disposed for receiving portions of said power stream from said interaction region as a function of power stream deflection in said interaction region; and

40 first and second control nozzles superposed one on the other and arranged to issue control fluid applied thereto into impingement against said power stream in said interaction region at locations which are equidistant from said power nozzle means.
